ANDREW PETUS AND STEFAN MIZERAK, OF NEWARK, NEW JERSEY.

SICK-ROOM TABLE.

1,286,087.

Specification of Letters Patent. Patented Nov. 26, 1918.

Application filed July 15, 1915. Serial No. 40,005.

To all whom it may concern:

Be it known that we, ANDREW PETUS and STEFAN MIZERAK, both subjects of the King of Hungary, and residents of Newark, in the 5 county of Essex and State of New Jersey, have invented new and useful Improvements in Sick-Room Tables, of which the following is a specification.

This invention relates to a sick room table 10 and has as its object to provide a table easily attachable to and detachable from a metallic bedstead as generally used in hospitals, sick rooms, etc., adjustable in various positions, adapted to be used for various purposes also 15 when detached from the bed-stead, simple of construction, cheap to manufacture and easy to handle.

With the foregoing and other objects in view, the invention consists in the particular 20 construction, combination and arrangement of parts hereinafter more specifically described and shown in its preferred form in the accompanying drawing, in which:

Figure 1 is a perspective view of our device attached to a part of a bed-stead, fragmentally shown, and Fig. 2 is a detail view of the mode of attachment, being a vertical cross section taken on the line 2—2 of Fig. 1, on an increased scale and showing some parts 30 in an altered position.

The same part is designated by the same reference character throughout the separate views.

Referring more particularly to the drawing, 3 is a part of the angle iron frame of a metallic bedstead to which is attached a clamp 4, comprising an upper part 5 of substantially L-shaped cross section one longitudinal edge 6 of which is bent under, adapted 35 to clamp the edge of the upper, horizontal portion of the frame 3, and a lower part 7 having its bottom edge 8 turned upward, adapted to clamp the edge of the lower, vertical portion of the frame 3. The part 7 has 40 attached to it screw bolts 9 projecting through and adapted to slide in vertical slots 10 provided in the part 5, so that the two parts are susceptible of a vertical sliding and of a tilting movement in respect to 45 each other and may be secured together, in the required position, by wing nuts 11 applied to the screw bolts 9.

Owing to this arrangement, the clamp 4 can easily be attached to the bed-stead by loosening the wing nuts 11, sliding the part

7 down on the part 5 as far as the slots 10 will allow, hooking on the part 6 to the horizontal upper portion of the frame 3, at an angle thereto, as seen in Fig. 2, then raising up the part 7 until the clamp lies close 60 against the frame 3 and, finally, tightening the wing nuts 11. By a reversed process the clamp can easily be detached from the bedstead. It is also obvious that when the clamp 4 is attached to the frame 3, it may be 65 moved along the entire length thereof, without the need of detaching it, by loosening the wing nuts and extending the clamp, and it may be fixed at any part of the length of the frame by raising the part 7 of the clamp 70 and tightening the wing nuts.

The part 7 of the clamp 4 carries a horizontal arm 12, to the outer end of which is attached a vertical tube 13. The latter carries, inserted into its upper end, slidably and 75 rotatably therein, a vertical rod 14 adjustable in various positions by means of a winged set screw 15.

Connected to the upper end of the rod 14 by hinge-parts 16 and 17, is a table top 18 80 having one longitudinal edge bent at an angle as at 19 so as to form a guard rail which serves as a support to a book or music sheet and at the same time is adapted to prevent articles sliding off the table top or 85 being accidentally brushed off same when in a horizontal position.

A semi-annular guide member 20 is secured to the bottom surface of the table top 18 and drawn freely slidably through a slot 90 21 provided in the rod 14. A winged set screw 22 inserted into the rod 14 and projecting into the slot 21 serves for securing the table top 18 at any desired angle to the rod 14, as may be clearly seen from the drawing. 95

A leg 23 having a base 24 is inserted into the lower end of the tube 13 and adjustable therein by means of the winged set screw 25. This leg and base serve to give the device additional stability when attached to a bed-stead and also to allow its use detached therefrom. It can easily be removed, if required, for cleaning the floor under the base or similar purposes. 100

It is obvious from the foregoing, that our table, when attached to a bed, may be used as a dining table, when the table top is adjusted in a horizontal position and swung over the bed, or as a side table for keeping 110

medical instruments and the like thereon, when swung away from the bed. Also as a reading and writing desk, when the table top is adjusted in an oblique position, at 5 various angles according to the convenience of the user, and, finally, detached from the bedstead, it may be used similarly for various purposes, notably also as a music stand.

It is understood that while we have thus 10 shown and described the preferred form of our invention, we do not want to be limited to the mechanical details thereof, but may resort to such modifications and alterations as come within the scope of the claim here- 15 unto appended.

We claim:

A sick room table comprising, in combination, a bracket adapted to be removably attached to a bedstead frame, a vertical sleeve at the free end of said bracket, a rod slidably inserted in the top opening of said sleeve, a table top carried by said rod, and a leg, having a base, slidably and adjustably inserted in the bottom opening of said sleeve, removable therefrom, and adapted to support said table independently from said bracket.

ANDREW PETUS.
STEFAN MIZERAK.
